UNITED STATES PATENT OFFICE.

ENDFRED LUNDBERG, OF WESTFIELD, NEW YORK, AND JUSTUS HATTEMER,
OF WEST NEW YORK, NEW JERSEY, ASSIGNS TO HARDMAN, PECK &
COMPANY, OF NEW YORK, N. Y., A CORPORATION OF NEW YORK.

EXPRESSION-BOX.

No. 853,814.

Specification of Letters Patent.

Patented May 14, 1907.

Application filed November 6, 1906. Serial No. 342,279.

To all whom it may concern:

Be it known that we, ENDFRED LUNDBERG, a citizen of the United States, residing at Westfield, county of Chautauqua, and State of New York, and JUSTUS HATTEMER, a citizen of the United States, residing at West New York, county of Hudson, and State of New Jersey, have invented certain new and useful Improvements in Expression-Boxes; and we do hereby declare the following to be a full, clear, and exact description of the invention, such as will enable others skilled in the art to which it appertains to make and use the same.

This invention relates to expression boxes for controlling a divided action of self-playing musical instruments and has for an object to provide a device embodying improved means for regulating the degree of exhaust applied to the pneumatics regulating the action.

A further object of the invention is to provide in a musical instrument having a divided action, valves of improved structure for controlling the exhaust at either end of the action independently of the other end.

A further object of the invention is to provide in a device of the class an expression box communicating with a light and heavy exhaust, and with valves arranged to control the exhaust and to put the action into communication with either the light or heavy exhaust and controllable by the operator.

With these and other objects in view the invention comprises certain other novel constructions, combinations and arrangements of parts, as will be hereinafter fully described and claimed.

In the drawings:—Figure 1 is a view of the improved expression box with one side formed with portions broken away to show the operating parts. Fig. 2 is a longitudinal, transverse section taken on line 2—2 of Fig. 1. Fig. 3 is a slightly modified form of the expression box showing the valve operated by gravity and controlled by primary pneumatics, and shown partly in side elevation and partly in vertical longitudinal section.

Like characters of reference designate corresponding parts throughout the several views.

The expression box forming the subject-

matter of this application comprises an outer box or casing 10 of any approved size and form, and having an opening 11 in communication with the light exhaust and openings 12 and 13 in communication with the heavy exhaust.

The opening 11 from the light exhaust opens into a chamber 14 formed within the casing 10 by partitions 15 and 16, disposed upon opposite sides of the opening 11 the said opening communicating with the chambers 17 and 18 upon opposite sides of the chamber 14, through the said chamber 14 and passages 19 and 20.

The openings 19 and 20 are closed, respectively, by means of flap valves 21 and 22 opening inwardly within the chamber 14 and adapted to close the openings against the passage of air from the chamber 14 to the chambers 17 and 18.

The chambers 17 and 18 communicate with adjacent chambers 23 and 24, respectively, through passages 25 and 26 with which chambers the openings 12 and 13 from the heavy exhaust are also in communication. Within the chambers 23 and 24 are disposed puppet valves 27 and 28, respectively, arranged to close the openings 25 and 26 between the said chambers 23 and 24, and the chambers 17 and 18, respectively. The puppet valves 27 and 28 are respectively mounted upon valve stems 29 and 30 having their extremities slidably mounted within keepers 31 and 32 and with opposite ends in communication with pneumatics 33 and 34. The pneumatics 33 and 34 are disposed over chambers 35 which said recesses communicate by means of passages 36 with means for admitting atmospheric air to the chambers 35 beneath the pneumatic 33 and 34.

In the form shown in Figs. 1 and 2 the valve stems 29 are preferably mounted to move horizontally and actuated by means of springs 37 and 38 so that the valves 27 and 28 are held normally and yieldingly open by the said springs and with the passages 25 and 26 forming normal communication between the chambers 23 and 24 and the chambers 17 and 18 respectively.

The form shown in Figs. 1 and 2 is the simpler form, wherein the chambers 35 are in direct communication with the atmosphere by

means of tubes 39 and 40 and by any other approved connection as the flexible tubes 41 and 42 by means of which the direct communication with the atmosphere may be closed 5 at will. The chambers 35 are also in communication with the chambers 23 and 24 through bleeders 43 whereby the degree of exhaustion in the chambers 23 and 24 and the chambers 35 is equalized and the springs 10 37 and 38 permitted to act to hold the valves 27 and 28 normally open. When atmospheric air is admitted through the connections conventionally indicated by the flexible tubing 41 and 42 into the chamber 35, the exhaustion upon that side of the pneumatics 33 and 34 is temporarily overcome and the atmospheric pressure within the chambers 35 acting upon the pneumatics 33 and 34 closes the valves 27 and 28 to thereby close the 15 openings 25 and 26. Under normal conditions the heavy exhaust acting against the valves 21 and 22 hold said valves closed against the tension of the light exhaust in the chamber 14 so that the exhaust is from the 20 action through openings 44 and 45 which connect with the respective sections of the divided action, the chambers 17 and 18, the openings 25 and 26 into the chambers 23 and 24, and outwardly through the openings 12 25 and 13 to the main heavy exhaust chamber. When, however, the valves 27 and 28 are closed by reason of the admission of air to the chambers 35 the openings 25 and 26 being thereby closed the light exhaust through 30 the opening 11 opens the flap valves 21 and 22 so that the exhaust is then from the action through the openings 44 and 45, the chambers 17 and 18, the openings 19 and 20 into the chamber 14 and outwardly through 35 the opening 11 to the main light exhaust chamber.

For closing communication between the expression box as a whole and the action during re-wind valves 46 are arranged to close 40 the openings 44 and 45 and controlled by the valve stem 47 connected with any approved portion of the mechanism as shown in Fig. 3. In the structure shown at Fig. 3, two other chambers 49 and 50 are provided in communication with the chambers 23 and 24 through 45 openings 51 and 52 and within which said chambers 49 and 50 are disposed primary valves 53 and 54. The primary valves 53 and 54 are mounted upon valve stems 55 and 56 and are arranged to close openings 57 and 58 with the atmosphere from the inside, the said valve stems carrying also valves 59 and 60 arranged to close the said openings from the outer side. The valve stems 55 and 60 56 have their extremities slidably mounted within keepers 61 and 62, and their opposite ends in engagement with pneumatics 63 and 64.

The pneumatics 63 and 64 are mounted 65 within chambers 65 which are in communica-

tion with the chambers 49 and 50 through bleeders 66 and 67, and with the atmosphere by means of passages 68 and tubes 69 and 70.

It will be understood that the chambers 49 and 50 are under continual exhaust from the heavy exhaust chamber through the passages 12 and 13, and 51 and 52, so that with the primary valves in the position shown in Fig. 3, the pneumatic 34 is subjected to exhaust from the chamber 50 through the passage 58 and the passage 36, while the exhaust upon opposite sides of the pneumatics 63 and 64 is equalized through the bleeders 66 and 67. So long as the tubes 69 and 70 are closed to the atmosphere the valves 53 and 54 remain in the position shown in the figure, but when communication is open to the atmosphere the exhaust tension within the chamber 65 is relieved and the exhaust tension within the chambers 49 and 50 raises the pneumatics 85 63 and 64 to close the openings 57 and 58 by means of the valves 53 and 54 and simultaneously raises the valves 59 and 60 so that the openings 57 and 58 are in communication with the atmosphere and the passages 36 and 90 chambers 35 are also relieved of tension so that the exhaust tension within the chambers 23 and 24 raises the pneumatics 33 and 34, as hereinbefore described.

From the above description it would appear that both ends of the action are simultaneously subjected to either the light or the heavy exhaust and such may be accomplished in the manner described, but it is to be understood that opposite sides of the expression box constitute substantially independent controlling means, so that both ends of the action may be simultaneously subjected to either degree of exhaustion, as described, or either end may be subjected to the heavy exhaust while the opposite end is subjected to the light exhaust by manipulating the valve upon one side only of the expression box, as described.

What I claim is:—

1. In a mechanism of the class described, a divided action, a high tension reservoir and a low tension reservoir, ducts communicating with the divided action, a chamber arranged for communication with the low tension reservoir, and having openings communicating with the ducts, valves arranged to close the openings between the low tension chamber and the ducts, chambers in communication with a high tension reservoir and with the ducts, valves arranged to close the communication between the high tension chambers and the ducts, and pneumatics arranged to control the valves governing communication between the high tension reservoir and the ducts.

2. In a mechanism of the class described, a divided action, a high tension reservoir and a low tension reservoir, ducts arranged for communication with the divided action, a

chamber in communication with the ducts and communicating with the low tension reservoir, flap valves opening within the chamber and arranged to close communication between the low tension chamber and the ducts, chambers in communication with the ducts, and communicating with the high tension reservoir, puppet valves within the high tension reservoir chambers, and positioned to close the communication between the high tension chambers and the ducts, and pneumatics arranged to actuate the puppet valves.

3. In a mechanism of the class described, a 15 divided action, a high tension reservoir and a low tension reservoir, ducts communicating with the divided action, a chamber in communication with the ducts, and also in communication with the low tension reservoir, 20 flap valves within the low tension chamber, and arranged to govern the communication between the low tension chamber and the ducts, chambers in communication with the ducts and also in communication with the 25 high tension reservoir, puppet valves disposed within the high tension chamber and positioned to close communication between such chambers and the ducts, pneumatics disposed within the high tension chambers 30 and arranged to actuate the puppet valves, and means for actuating the pneumatics.

4. In a mechanism of the class described, a divided action, a high tension reservoir, and a low tension reservoir, ducts communicating 35 with the divided action, a chamber in communication with the ducts and also communicating with the low tension reservoir, valves disposed within the low tension chamber and opening inwardly and positioned to govern communication between the low tension chamber and the ducts, chambers in communication with the ducts and arranged for independent communication with the high tension reservoir, valves disposed within the high

tension chambers and arranged to govern communication between the high tension chambers and the ducts, pneumatics disposed within the high tension chambers, and arranged to actuate the valves, means for equalizing the exhaust tension upon opposite sides of the 45 pneumatics, and means to overcome the exhaust upon one side of the pneumatics.

5. In a mechanism of the class described, a divided action, a high tension reservoir and a low tension reservoir, ducts communicating with the divided action, a chamber in communication with the ducts and arranged for communication with the low tension reservoir, valves mounted within the low tension chamber and arranged to open inwardly, 50 chambers in communication with the ducts and arranged for communication with the high tension reservoir, secondary pneumatics disposed within the high tension chamber, and provided with an exhaust chamber and 55 passage leading therefrom, valves carried by the secondary pneumatics and governing communication between the high tension chambers, and the ducts, other chambers in communication with the high tension chambers, primary pneumatics disposed within the last-mentioned chambers, means for equalizing the exhaust upon opposite sides of the primary pneumatics, valves carried by the primary pneumatics and arranged to 60 establish communication from the secondary pneumatic passage alternately with the exhaust and with the atmosphere, and means to overcome the exhaust within the primary pneumatics.

In testimony whereof we affix our signatures in presence of two witnesses.
